UNITED STATES PATENT OFFICE.

OTTO H. ESCHHOLZ, OF WILKINSBURG, PENNSYLVANIA, ASSIGNOR TO WESTINGHOUSE ELECTRIC & MANUFACTURING COMPANY, A CORPORATION OF PENNSYLVANIA.

CIRCUIT INTERRUPTER.

Application filed April 6, 1923. Serial No. 630,267.

To all whom it may concern:

Be it known that I, Otto H. Eschholz, a citizen of the United States, and a resident of Wilkinsburg, in the county of Allegheny and State of Pennsylvania, have invented a new and useful Improvement in Circuit Interrupters, of which the following is a specification.

My invention relates to fluid-insulated circuit interrupters and more particularly to means for utilizing the gases generated within a circuit interrupter for expelling such gases as may be confined above the fluid level of the circuit interrupter.

One object of my invention is to provide a fluid-filled circuit interrupter that is adapted to expel confined gases in advance of arc gases generated within the circuit interrupter.

Another object of my invention is to provide a circuit interrupter in which arc gases generated therein exert a uniform pressure upon gases confined within the circuit interrupter and above the fluid level.

It is also an object of my invention to provide means whereby atomizing of the fluid within the circuit interrupter is minimized upon the formation of electrical arcs therein.

In carrying my invention into practice, I provide a diaphragm which is normally submerged in an insulating fluid and which is adapted to move axially of the tank upon the formation of arc gases occurring during circuit interruption. The diaphragm is ar-

anged to have uniform axial movement of the tank for a limited distance and means may be provided for imparting an irregular movement to the diaphragm during the latter portion of its travel.

Many circuit interrupters are designed in such manner that the gases generated upon the occurrence of an electrical arc are utilized to cause the fluid to exert a piston-like effect upon such gases as may be confined above the fluid level. The confined gases are thereby driven off before they come in contact with hot arc gases thereby eliminating the danger of explosions by reason of the mixture of an oxygen-containing gas and the hot combustible arc gases.

It has been found that conditions may arise, such as small total arc energy, low rate of gas generation or diverting superstructure, remitting in the incomplete func-

tioning of the fluid head as a piston by reason of the fact that the arc gases do not act uniformly over the entire surface. That is, the gas escape is irregular causing but a partial displacement of confined gases by the moving fluid. The failure of the generated gases to exert a substantially uniform pressure upon the oil head results in the escape of the arc gases in small volumes with the resultant breaking up and atomization of the fluid surface and thus facilitating the production of an explodable mixture of arc gases, confined gas and fluid spray within the circuit interrupter.

My invention contemplates the elimination of these difficulties by providing a diaphragm which will impart a true piston-like motion at all points of the surface fluid.

The single figure of the drawings is a side view, partially in elevation and partially in section, of a circuit interrupter embodying my invention.

In the preferred embodiment of my invention, a circuit interrupter comprises a tank 2, a cover 3, relatively movable contact members 5 and 6, electrical conductors 7 communicating therewith, and actuating mechanism 8 therefor. The tank 2 contains a suitable insulating fluid 9, in which the contact members 5 and 6 are submerged. Any suitable venting means 11, such as a muffler, is provided for the circuit interrupter. However, the venting means 11 is preferably disposed eccentrically of the tank 2.

A diaphragm 12 is normally supported by brackets 13 above the contact members 5 and 6 and near the surface of the fluid. This position is indicated at A. Suitable perforations 14 and slots 15 are provided for the escape of gas particles and to permit the diaphragm to move longitudinally of the tank. In the event of the fluid level falling below the diaphragm, the diaphragm functions as a barrier between the arc and confined gases as well as a piston. A stop member 16 is provided for a purpose hereinafter described.

In the operation of a circuit interrupter equipped with my invention, manipulation of the mechanism 8 causes a relative movement between the contact members 5 and 6 that is accompanied by the formation of an electrical arc. The gases generated by this arc tend to rise through, and violently agi-

tate, the fluid 9. These gases encounter the diaphragm 12 in its normal position. A certain portion of the gas escapes through the perforations 14 and 15 but the greater portion thereof is entrapped below the diaphragm. As the quantity of gas thus generated is considerable, it exerts sufficient pressure to lift the diaphragm upwardly from the brackets 13, or axially of the tank 2.

The liquid above the diaphragm is carried with it and acts as a piston in driving out the confined gases which normally fill the space within the circuit interrupter above the fluid level. Movement of the diaphragm continues uniformly through an intermediate position indicated by dotted lines at B until one edge of the diaphragm encounters the stop member 16. The stop member may produce an irregular or tilting movement of the diaphragm thereafter, resulting in its assuming the inclined position indicated by broken lines at C. The tilting movement of the diaphragm 12 sweeps the gases in the direction of the venting means 11.

The fluid which has been carried in advance of the diaphragm is directed toward the lower edge of the diaphragm while the free edge is blown free from the fluid, thereby permitting the escape of the arc gases to the venting device 11.

The velocity imparted to the diaphragm and the suspended oil during their travel from its normal position to its uppermost position, is such that the confined oxygen-bearing gases, which normally fill the space above the fluid level of the circuit interrupter, are driven off without any material amount of atomization of the fluid. The arc gases may then be permitted to come in contact with the muffling device 11 without incurring the danger of exploding with oxygen containing gases. The arc gases are also somewhat cooled, by coming in contact with the diaphragm 12, by reason of the energy expended in lifting the diaphragm and the entrapped fluid, and also by the cooling of certain particles of the gas which have escaped through the openings 14 and 15.

Accordingly, I have provided a circuit interrupter having means for providing a true piston-like action of the confined fluid and for utilizing this action in driving off the gases usually found above the fluid level before these gases can come into contact with the hot arc gases generated within the circuit interrupter.

It will be apparent that various modifications may be made in details and general arrangement without departing from the spirit and scope of the invention, as set forth in the appended claims.

I claim as my invention:

1. In a circuit interrupter, the combination with a closed tank, a fluid in said tank, relatively movable contact members immersed in said fluid, and venting means for said tank, of a diaphragm having uniform movement axially of said tank for a limited distance and means for causing an irregular movement of said diaphragm beyond a predetermined point.

2. In a circuit interrupter, the combination with a closed tank, a fluid in said tank, relatively movable contact members immersed in said fluid, and venting means for said tank, of a diaphragm having a uniform movement axially of said tank for a limited distance, whereby the gases within the tank and above the diaphragm are compressed, said diaphragm having a subsequent movement for sweeping the compressed gases towards the venting means.

3. In a circuit interrupter, the combination with a closed tank, a fluid in said tank, relatively movable contact members immersed in said fluid, and venting means for said tank disposed eccentrically thereof, of a diaphragm having a movement during which the gases within the tank and thereabove are compressed and a subsequent movement for sweeping the compressed gases towards the venting means.

4. In a circuit interrupter, the combination with a closed tank, a fluid in said tank, relatively movable contact members immersed in said fluid, and venting means for said tank disposed eccentrically thereof, of a diaphragm having movement axially of said tank, means projecting from the inner surface of the tank for normally supporting the diaphragm and means projecting from the inner surface of the tank at a different plane from the first means for arresting uniform movement of the diaphragm and causing it to describe a sweeping movement in the direction of the venting means upon the formation of an electrical arc between the contact members.

5. In a circuit interrupter, the combination with a closed tank, a fluid in said tank, relatively movable contact members immersed in said fluid, and venting means for said tank disposed eccentrically thereof, of a diaphragm having movement axially of said tank, means for supporting the diaphragm disposed within the tank, and means disposed at another point in said tank for arresting the uniform movement of the diaphragm and causing it to describe a sweeping movement towards the venting means upon the formation of an electrical arc between the contact members.

In testimony whereof, I have hereunto subscribed my name this 4th day of April, 1923.

OTTO H. ESCHHOLZ.
